(57) **CLAIM**

The ornamental design for a harness for supporting an electronic device, as shown and described.

DESCRIPTION

FIG. 1 is a top plan view of the harness for supporting an electronic device.

FIG. 2 is a bottom plan view of the harness for supporting an electronic device.

FIG. 3 is a front view of the harness for supporting an electronic device.

FIG. 4 is a rear view of the harness for supporting an electronic device.

FIG. 5 is a right view of the harness for supporting an electronic device in an open position.

FIG. 6 is a left view of the harness for supporting an electronic device in an open position.

FIG. 7 is a top perspective view of the harness for supporting an electronic device in an open position.

FIG. 8 is a bottom perspective view of the harness for supporting an electronic device in an open position.

FIG. 9 is a top plan view of the harness for supporting an electronic device in a closed position.

FIG. 10 is a bottom plan view of the harness for supporting an electronic device in a closed position.

FIG. 11 is a right side view of the harness for supporting an electronic device in a closed position.

FIG. 12 is a left side view of the harness for supporting an electronic device in a closed position.

FIG. 13 is a front view of the harness for supporting an electronic device.

FIG. 14 is a rear view of the harness for supporting an electronic device.

FIG. 15 is a side perspective view of the harness for supporting an electronic device in a closed position.

FIG. 16 is a side perspective view of the harness for supporting an electronic device in a closed position; and,

FIG. 17 shows the harness for supporting an electronic device in use.

The broken lines shown in FIG. 17 show environment and forms no part of the claimed design.
